Primary Examiner — Jennifer Rivard*Assistant Examiner* — Jennylo M Binas(74) *Attorney, Agent, or Firm* — David & Raymond Patent Firm; Raymond Y Chan(57) **CLAIM**

The ornamental design for a skimmer frame as shown and described.

DESCRIPTION

FIG. 1 is a top perspective view of a skimmer frame showing my new design;

FIG. 2 is a front view thereof;

FIG. 3 is a rear view thereof;

FIG. 4 is a left elevation view thereof;

FIG. 5 is a right elevation view thereof;

FIG. 6 is a top view thereof; and,

FIG. 7 is a bottom view thereof.

The broken lines shown in the figures are for the purpose of illustrating portions of the skimmer frame and form no part of the claimed design.

1 Claim, 5 Drawing Sheets(56)
